PIPE FOR TOBACCO

Frank M. Ashley, Great Kills, Staten Island, N. Y.,
assignor to Lewis Gompers, as trustee

Application April 24, 1936, Serial No. 76,149

3 Claims. (Cl. 131—202)

My invention relates to pipes in which tobacco is smoked.

The object of my invention is to provide a pipe in which a filter may be used to absorb the juices produced in smoking the tobacco, and also may be used in the event that no filters are available, without resorting to separate attachable parts.

A further object is to provide a construction in which the bowl of the pipe may be made of briar-wood, and the stem and mouth-piece of moulded plastic material; the construction being such that the filter is held entirely or almost entirely in the stem portion.

A further object is to provide a pipe in which the filter is inserted and removed from the stem of the pipe from the end on which the mouth-piece is carried without removing the mouth-piece or stem from the bowl of the pipe, and also providing means whereby the opening thru which the filter is inserted in the stem may be closed when the filter is removed.

A further object is to provide a pipe having a curved stem or mouthpiece in which the mouth-piece is carried in the same position relative to the bowl, whether or not the opening thru which the filter is inserted in the stem is in an open or closed condition, and also to form the mouth-piece in such a manner as to almost completely conceal the said opening.

In the forms shown in the present drawing forming a part of the specification, my construction embodies a valve for closing the opening thru which the filter is inserted when the filter is not in use, without closing the passage thru the stem and mouth-piece.

Further objects and advantages of the construction will be hereinafter set forth.

Fig. 1 is a longitudinal sectional view thru a pipe disclosing my invention in one form of construction in which the mouth-piece only is rotated to open or close the opening thru which the filter is passed in inserting it in the stem.

Fig. 2 is a view similar to that shown in Fig. 1 except that a thin tube is used in the construction.

Fig. 3 is a longitudinal sectional view of a construction in which a curved mouth-piece is used instead of a straight one, and is shown with the filter in position in the stem.

Fig. 4 is a view of the same construction as that illustrated in Fig. 3 showing the stem rotated one half turn relative to the bowl and mouth-piece, the valve being closed.

10 indicates the bowl of a pipe which may be made of briar-wood or other suitable material,

and is formed with a long stem 10' integral therewith when the mouth-piece 11 is straight, as illustrated in Figures 1 and 2, and made very short when the mouth-piece is curved, as illustrated in Figs. 3 and 4.

In Figure 1, the stem portion 10' is provided with an enlarged bore 12 communicating with the shoulder 13 by a small passage 14, and a cylindrical socket 15 is formed to receive the cylindrical end 11' of the mouth-piece 11.

The inner end of the mouth-piece is formed with a chamber 16 in open communication with the passage 16' of smaller diameter leading therethru.

A hole 17 of smaller diameter than the normal diameter of the filter 18, is formed in the wall of the stem and a similar hole 19 is formed in the wall of the mouth-piece in direct communication with the chamber 16 and in alignment or registration with the hole 17.

Therefore, when the filter is removed, the mouth-piece may be rotated one half revolution relative to the stem, thus closing the passage thru said holes; the construction providing a valve, as will be readily understood.

The construction shown in Figure 2, is practically the same as that shown in Figure 1, the difference being that in Figure 2, I use a thin aluminum tube 20 which fits tightly in the chamber 16 and is rotatable in the socket 15, or it may be made to fit in rotatable relation directly in the bore 12 of the stem if desired, due to the thin wall of the metal, it takes up very little space in the bore, as will be readily understood.

Referring now to Figure 3, the stem 10' is made very short to reduce the cost of the bowls, and the socket 15 extends nearly to the chamber 13.

A middle-stem 21 is formed with the bore 12 and with a cylindrical end 22 which fits in the stem 10' in rotatable relation, and its opposite end is formed cylindrical as shown at 23, and is also provided with an end wall 24 having an opening 27 leading therethru and located at one side of the medial line thru the bore 12.

The oppositely disposed holes 26 extend thru the cylindrical wall, either of which may be caused to register with the inner end of the passage 16' formed in the mouth-piece.

The mouth-piece shown in Figures 3 and 4, is formed with a cylindrical socket 23' into which the cylindrical end 23 fits in rotatable relation, and is also provided with an opening 27 formed on the under side thereof which registers with the opening 25 in the position shown in Figure 3, and is out of registration when in the position 55

shown in Figure 4, the change being caused by rotating the middle stem one half revolution.

The mouthpiece is also formed with side walls 28 which shield the opening 24 in the manner shown.

The relative length of the bore 12 and passage 16' are such that the filter may be used to clean the passage 16' before its insertion in the bore, if desired.

10. The filters used are preferably made of the same material and diameter, etc. as commonly used for pipe cleaners, but a filter length of two inches has been found to be ample in length to perfectly filter and absorb the juices generated or liberated from the tobacco in smoking the same.

15. By making the opening thru the valve slightly smaller than the filter bore, which should be about three sixteenths of an inch in diameter, the filter will fit snugly in the valve opening or ports, and very little air will pass thru the said opening in the act of smoking, even tho no enlarged end is formed on the filters.

Having thus described my invention I claim as new:

20. 1. A pipe of the character described comprising a bowl, a stem, and a mouth-piece, said stem

having a bore formed to receive a filter with the longitudinal axis of the major portion of the filter in parallel relation to the axis of the bore, and having an opening thru which a filter may be inserted in the bore, said stem and mouth-piece 5 constituting means for closing said opening when the filter is removed from the bore without removing the mouth-piece from the stem, said opening being controlled by the rotation of the mouth-piece relative to the stem.

2. A pipe of the character described comprising a bowl, a stem rotatable relative to the bowl, and a mouth-piece rotatable relative to the stem, said mouth-piece being curved in form and having an opening in its outer end wall under the 15 passage therethru, said stem having an enlarged bore to hold a filter and provided with an end wall having an opening adapted to register with the opening in the mouth-piece; said openings forming a valve operative by rotating the stem relative to the mouth-piece.

25. 3. The construction defined by claim 2, together with said mouth-piece having depending side walls located adjacent the opening below the passage therethru, to shield the opening from view.

FRANK M. ASHLEY.
